UNITED STATES PATENT OFFICE

141,952

DESIGN FOR A TARGET GAME DEVICE

Benjamin P. Barrett, Salem, Ohio

Application April 7, 1945, Serial No. 118,891

Term of patent 14 years

(Cl. D34—5)

To all whom it may concern:

Be it known that I, Benjamin P. Barrett, a citizen of the United States, residing at Salem, in the county of Columbiana and State of Ohio, have invented new, original, and ornamental Design for a Target Game Device, of which the following is a specification, reference being had to the accompanying drawing, forming part thereof.

In the drawing:

I claim:

The ornamental design for a target game device, as shown.

BENJAMIN P. BARRETT.
